UNITED STATES PATENT OFFICE.

MURRELL R. DE FRANCE, OF BELLEVUE, PENNSYLVANIA.

BRAKE-SHOE.

1,303,172.

Specification of Letters Patent.

Patented May 6, 1919.

Application filed January 10, 1918. Serial No. 211,277.

To all whom it may concern:

Be it known that I, MURRELL R. DE FRANCE, a citizen of the United States, and a resident of Bellevue, in the county of Allegheny and State of Pennsylvania, have made 5 a new and useful Invention in Brake-Shoes, of which the following is a specification.

This invention relates to brake shoes.

It is now customary to manufacture brake 10 shoes having an inclosing casing either formed of cast metal or stamped from sheet metal and a filling formed of frictional material pressed into the casing.

Frictional materials for brake shoes are 15 familiar to those skilled in the art and generally consist of a number of frictional materials such as iron borings and finely divided asbestos held together by means of a binder such as resin or resins and drying 20 oils. It has been found in practice that the outer or frictional surface of these composition brake shoes have a much greater resistance to wear than the inner portions thereof. It is my belief that the exposure of the outer 25 surface to the action of air in some manner seasons or ages the composition thereby giving to it its wear resisting qualities.

An object of this invention is to provide means whereby the entire mass of the frictional filler may be uniformly aged or cured 30 so as to be uniformly wear resisting throughout.

For the purpose of illustrating this invention I have included a sheet of drawings in 35 which Figure 1 is a view in sectional elevation of a brake shoe embodying this invention, Fig. 2 is a top plan view of the same, and Fig. 3 is a cross sectional view taken on line 3-3 of Fig. 2.

40 In carrying out this invention I utilize a casing 4 either made as a casting or pressed from sheet metal. The back of the casing is provided with perforations 5 arranged in any suitable manner and this casing is filled 45 with suitable frictional material 6 preferably pressed into the casing. The casings are preferably placed over a form provided with fingers which project through perforations 5. These are preferably of varying 50 lengths so that some will project entirely through the interior of the casing and some only partially through. The filling material is then inserted in the casing and pressure exerted by means of a die and press.

The die is preferably provided with holes 55 registering with the fingers which extend entirely through the casing so that the filler can be compressed around the fingers. When the die is removed the casing with its filling may be lifted from the form and the 60 filler will thus be provided with perforations some of which extend entirely through the shoe while some extend only partially through from the back toward the front. In this manner the filler is provided with air 65 holes so that air may come in contact with the interior thereof and aid in aging or seasoning the same.

The perforations in the back of the casing may be staggered as shown in Fig. 2 or they 70 may be arranged in any manner found desirable.

The channels also allow the circulation of air in contact with the inner portion of the mass of the filler and this air serves to carry 75 away the heat or a portion of the same generated during the application of the brake shoes. It is believed that this heat has a tendency to soften the binders used in the 80 filler material. By carrying away this heat the effective life of the brake shoes is materially increased.

Having thus described my invention what I claim is—

1. In a brake shoe, an inclosing metal case 85 and a filler for said case formed of frictional material containing a binding agent adapted to be hardened by exposure to the air, said material having channels extending thereinto for the purpose of admitting air to the 90 interior of said material.

2. In a brake shoe, an inclosing metal case and a filling of frictional material held together by a binding agent adapted to be improved by exposure to the air; said filling 95 material having air channels extending thereinto from the back of said shoe.

3. In a brake shoe, an inclosing perforated metal case, a filler of frictional material within said casing and containing a binder 100 adapted to be improved by exposure to the air; said frictional material being provided with air channels registering with the perforations of said casing.

4. In a brake shoe, an inclosing metal case 105 having perforations in the back thereof and a filler of frictional material provided with air channels registering with said perfora-

tions and extending into said filler toward the front face thereof.

5. In a brake shoe, an inclosing metal casting having a perforated back section and a ⁵ filler of frictional material containing a binding agent and provided with air channels registering with the perforations of said

back section and extending through said filler.

In testimony whereof, I have hereunto 10 subscribed my name this 4th day of January, 1918.

MURRELL R. DE FRANCE.
